STEPHEN E. CIBULAS, OF BRIDGEPORT, CONNECTICUT.

WINDOW-OPERATING MECHANISM.

1,262,306.

Specification of Letters Patent.

Patented Apr. 9, 1918.

Application filed February 25, 1918. Serial No. 218,979.

To all whom it may concern:

Be it known that I, STEPHEN E. CIBULAS, a citizen of the United States, residing at 604 Wood Ave., Bridgeport, county of Fairfield, State of Connecticut, have invented an Improvement in Window-Operating Mechanisms, of which the following is a specification.

This invention has for its object to provide simple and inexpensive mechanism for opening and closing windows which shall be easy to operate and practically impossible to get out of repair, and especially to provide mechanism of this character, which shall extend inward but little distance from the wall of the building and occupy but little space, and in which all lateral strain and pressure upon the window or windows, at the beginning of the opening movement, shall be eliminated, so that there will be no jamming of the windows against the casings, each window being free to swing at all portions of its movement.

With these and other objects in view, I have devised the novel window operating mechanism which I will now describe, referring to the accompanying drawings forming a part of this specification and using reference characters to indicate the several parts.

Figure 1 is an elevation illustrating the application of my novel opening mechanism to a window;

Fig. 2, a section on the line 2—2 in Fig. 35 1 looking in the direction of the arrows;

Fig. 3, a section on an enlarged scale on the line 3—3 in Fig. 1 looking in the direction of the arrows;

Fig. 4, a view corresponding with Fig. 1, 40 but showing the window in the open position, and

Figs. 5 and 6 are views corresponding with Fig. 2, but showing modifications in details of construction.

45 10 denotes the operating rod, so called, which in practice is ordinarily a pipe. This rod may be reciprocated longitudinally in any ordinary or preferred manner. In the present instance I have shown the movement 50 of the operating rod as produced by a rack and pinion, the pinion shaft being provided with a wheel over which an operating chain passes.

It will of course be understood that this 55 type of window operating mechanism is ordinarily used to open and close a plurality

of windows simultaneously, as in factories, halls, railroad stations and cars. The operating rod extends the entire length of the series of windows to be operated, and is provided at suitable distances with guides 20. In the present instance I have shown the guides as provided with grooved rollers between which the rod travels. The windows may swing on a horizontal axis, as shown in 65 the drawings, or on a vertical axis if preferred, and may be pivoted to swing on their centers, as shown, or if preferred they may be hinged at either top or bottom.

The operating rod is provided with a 70 bracket 11, the lower rail of the window sash with a bracket 12, and the window casting, just below the window opening, with a bracket 13. 14 denotes the operating arm, one end of which is pivotally connected, 75 either directly or indirectly, to bracket 12 on the window. The other end of the arm is pivoted to an angle plate 15, which is itself pivoted to bracket 11. It should be noted that the plane of oscillation of the operating 80 arm, with relation to the angle plate, is at right angles to the plane of oscillation of the angle plate with relation to the bracket, thus providing a universal joint between the operating rod and the operating arm. 16 denotes an angle plate pivoted to bracket 13 85 and 17 a telescopic arm, one end of which is pivoted to angle plate 16. The planes of oscillation of the telescopic arm with relation to angle plate 16 and of said angle plate with 90 relation to bracket 13, are at right angles to each other, thus providing a universal joint between the telescopic arm and the bracket. The pivot pin, indicated by 18, of the telescopic arm serves as a stop to limit the 95 inward movement of the sliding member of the telescopic arm, as will be clearly understood from Fig. 2.

In the form illustrated in Figs. 1, 2 and 4, the operating arm and the sliding member of the telescopic arm are pivoted to opposite sides of an equalizing plate, indicated by 19, which is itself pivoted to bracket 12 upon the window.

In use, when the operating rod is moved 105 toward the left from the position shown in Fig. 2, the equalizing plate will swing on its pivot toward the position shown in Fig. 4. This for the reason that the line of thrust of the operating arm is not in alignment with the telescopic arm. When thrust movement is applied to the operating arm,

it will be transmitted by the equalizing plate both to the window and to the sliding member of the telescopic arm. Inward movement of this member, however, is stopped 5 by pivot pin 18 so that all of the thrust is directed toward the window and will act to swing it directly outward, as shown in Fig. 4, and without imparting any lateral movement to the window. In fact 10 there is no possibility of the window jamming in the casing, but the thrust movement of the operating arm is exerted wholly upon the window to swing it to the open position. As the window swings outward, the 15 sliding member of the telescopic arm will be drawn outward, as shown in Fig. 4. The function of the telescopic arm therefore is to take the initial thrust of the operating arm at the beginning of the opening movement and transmit it to the window. The 20 equalizing plate is preferably provided with a stop shoulder 21, which engages bracket 12 on the window and limits the oscillation of the plate and the opening movement of 25 the window.

The form illustrated in Fig. 5 differs in that the equalizing plate is dispensed with and both the operating arm and the telescopic arm are pivotally connected to 30 bracket 12.

In the form illustrated in Fig. 6, the operating arm only is pivotally connected to bracket 12, the sliding member of the telescopic arm being pivotally connected to the 35 operating arm. The operation in both of these forms is substantially the same as where the equalizing plate is used, in that the initial thrust of the operating arm is first transmitted to the telescopic arm, the 40 inward movement of whose sliding member is stopped, and by which the thrust is transmitted to the window to move it to the open position.

Having thus described my invention, I 45 claim:

1. Window operating mechanism comprising an operating rod, an operating arm, a universal connection between said rod and one end of said arm, a telescopic arm, means 50 for universally connecting one end of the telescopic arm to a window casing, and means for pivotally connecting the operating arm and the telescopic arm to a window, the operating arm and the telescopic 55 arm being out of alinement so that thrust movement of the operating arm will be exerted to open the window.

2. Window operating mechanism comprising an operating rod, an operating arm, a 60 universal connection between said rod and one end of said arm, a telescopic arm, means

for universally connecting one end of the telescopic arm to a window casing, a stop to limit the inward movement of the sliding member of the telescopic arm, and means 65 for pivotally connecting the operating arm and the telescopic arm to a window.

3. Window operating mechanism comprising an operating rod, an operating arm, a universal connection between said rod and one end of said arm, a telescopic arm, means 70 for universally connecting one end of the telescopic arm to a window casing, and an equalizing plate pivoted to the window to which the operating arm, and the telescopic 75 arm are pivotally connected.

4. Window operating mechanism comprising an operating rod provided with a bracket, an angle plate pivoted to the bracket, an operating rod one end of which 80 is pivoted to the angle plate, a telescopic arm, means for universally connecting one end of said arm to a window casing, and means for pivotally connecting the other 85 ends of the operating arm and the telescopic arm to a window.

5. Window operating mechanism comprising an operating rod, an operating arm, a universal connection between said rod and one end of said arm, a telescopic arm, and 90 angle plate pivoted to one end of said arm, a bracket pivoted to the angle plate and adapted for attachment to a window casing, and means for pivotally connecting the operating arm and the telescopic arm to a window. 95

6. Window operating mechanism comprising an operating rod provided with a bracket, an angle plate pivoted to the bracket, an operating rod one end of which 100 is pivoted to the angle plate, a telescopic arm, means for universally connecting one end of said arm to a window casing, and an equalizing plate pivoted to the window to which the operating arm and the telescopic 105 arm are pivotally connected.

7. Window operating mechanism comprising an operating rod, an operating arm, a universal connection between said rod and one end of said arm, a telescopic arm, means 110 for universally connecting one end of the telescopic arm to a window casing, a bracket adapted for attachment to a window, and an equalizing plate pivoted to the bracket to which the operating arm and the telescopic 115 arm are pivotally connected and which is provided with a stop adapted to engage the bracket, for the purpose set forth.

In testimony whereof I affix my signature. 120

STEPHEN E. CIBULAS.
